UNITED STATES PATENT OFFICE

HOMER T. DARLINGTON, OF WEST CHESTER, PENNSYLVANIA, ASSIGNOR, BY MESNE ASSIGNMENTS, TO OIL CORPORATION OF AMERICA, A CORPORATION OF DELAWARE

APPARATUS FOR TREATING HYDROCARBONS

Application filed April 23, 1927. Serial No. 186,005.

I have invented a new and useful process and apparatus for the treatment of fluid hydrocarbons of which the following is a description:

lence, located in the terminal tubular member 8 beyond and above the line of circulation therethrough wherein the hydrocarbon does not circulate to any substantial degree, but owing to the motion communicated by the circulation in other parts of the chamber and the continuous or intermittent feeding of hydrocarbon thereto and discharge of hydrocarbon therefrom is in a state of turbulence.

This zone of non-circulatory turbulence may be so positioned in relation to the zone of active circulation that the movement therein has a churning effect. In some instances this is desirable and produces better results. This zone of non-circulatory turbulence may be, as shown, an integral part of one of the tubular sections of the reaction chamber.

12 is a means of discharging hydrocarbon vapors from the zone of non-circulatory turbulence and feeding them to a dephlegmator, separator or other apparatus for further treatment. 10 shows an optional oil level in the zone of non-circulatory turbulence, which level may vary as required by the character of hydrocarbon and working conditions employed, and 11 is an indicator or other means of ascertaining the oil level.

Valve controlled means 13 are provided for the introduction, as and when desired, of a catalyst, a gas, steam, or a treating or other agent. The addition of a catalyst, gas, steam, a treating or other agent, or two or more of them, may be made at the point indicated or at any other part of the reaction chamber, or to the zone of non-circulating turbulence alone. 15 shows valve controlled alternative means for introducing new stock, or stock that has been treated.

Heavy fractions, such, for example, as may be employed in the making of lubricating oil, deposited carbon, and any hydrocarbon it is not desired to treat further at the time may be withdrawn through the valve controlled outlet 16. Efficiency in the operation of my said process and the use of my said apparatus is promoted by controlling the temperature in the zone of non-circulatory turbulence, and provision is therefore made for the controlled regulation of temperature therein by the admission therein

at will of fresh oil or other stock through a valve controlled line 17. Any other approved method of controlling and regulating the temperature in this zone may be used 5 instead of the one shown and described.

I have sought to combine and arrange the several parts of this reaction chamber in the most convenient and practical manner for effective use, but I do not confine myself to 10 the embodiment of my invention shown, and I may vary the form and character of the several parts and the method of assembling them and still have an apparatus embodying the principles which make my apparatus 15 new and distinct.

This reaction chamber may, and ordinarily should, be insulated and it may have 20 means of heating (not shown) either direct or by heat interchange in any approved manner. While I prefer that hydrocarbon should be raised to a cracking temperature in a still before its introduction to the reaction chamber, it may be preheated in any 25 manner desired and the reaction chamber used as a combined still and reaction chamber. While mechanical means of circulation within the reaction chamber, other than that provided by the addition of a catalyst, 30 gas, steam or a treating agent when used, is ordinarily not required, the reaction chamber may have in it mechanical means of circulation, such as paddles, a propeller 18 or an impeller operated by an external source 35 of power, and it should be provided with such a means of circulation when not connected, as it is in the drawing, to a still or other preliminary treating apparatus having 40 such mechanical means of circulation.

I have found in actual practice that a multiplicity of tubular members arranged as 45 shown in the drawing promotes circulation, and when these parallel tubular members exceed two, the circulation of the hydrocarbons increases progressively from the place 50 of entry and in the tubes more distant therefrom is exceedingly active, and that this rapid circulation aids the cracking of hydrocarbon within the reaction chamber and causes the yield of greater quantities of more desirable products.

In the practical use of this reaction chamber and the practice of my process, I feed an oil stock, preferably continuously, but intermittently if desired, to a still of any 55 approved type, having suitable means of heating and applying pressure, and preferably, though not necessarily, mechanical means of promoting circulation. I maintain in the still a temperature and pressure conducive 60 to cracking and pass the oil at cracking temperature and pressure in liquid form through the portal 1a into the reaction chamber. I then circulate the oil, in such a way as to provide two or more circuits in heat exchange 65 relationship through the mergence and di-

vergent discharge of the circuits, one of which, if at a higher temperature than the other by reason of its discharge through the still, will transfer its heat to the other thereby obviating the necessity for passing the oil 70 contained in both of the circuits through the still or other heating appliance. In this way the hotter circuit is cooled by the cooler circuit which is itself heated by the hotter circuit and finally passes in the apparatus 75 as shown to the zone of non-circulatory turbulence already described. There it vaporizes and the vapors pass through a pipe line controlled by the valve 12, or other connection, preferably to a dephlegmator, but they 80 may pass to a separate or other apparatus for further treatment.

To aid in the cracking and the vaporizing, I introduce through means provided for that 85 purpose, at 13, or elsewhere if preferred, a catalyst, gas, steam or treating agent, or two or more of them, or I may, if I prefer, omit this addition.

I have found that circulation of the peculiar kind shown, the agitation of the hydrocarbons in a zone of non-circulatory turbulence and the presence of a treating agent in the hydrocarbon while circulating and also while in the zone of non-circulatory turbulence, each effectually contribute to the cracking and vaporization of the hydrocarbons 90 and each help to produce more and higher grade products than can be otherwise obtained, and that each one of them alone has some effect, but that they work more efficiently 95 when some or all are used in combination.

I claim:

1. An apparatus for cracking hydrocarbon oil comprising a pair of vertical tubes of large cross sectional area, one of the tubes being substantially longer than the other and the tubes being connected near the ends of the shorter tube so as to constitute an enlarged chamber adapted to contain a bulk supply of oil under super-atmospheric pressure and cracking temperatures for a prolonged period to effect substantial conversion thereof, means for cyclically supplying highly heated oil to the short tube, means for circulating oil cyclically through the short tube and part 105 of the longer tube, the upper portion of the longer tube being extended above the circulatory zone, and means for withdrawing vapors from the upper part of the longer tube.

2. An apparatus for cracking hydrocarbon oil comprising three vertical tubes of large cross-sectional area, one of the tubes being substantially longer than the other two, and the tubes being connected near the ends of the shorter tubes so as to constitute an enlarged 110 chamber adapted to contain a bulk supply of oil under super-atmospheric pressure and cracking temperatures for a prolonged period to effect substantial conversion thereof, means for cyclically supplying highly heated 115 oil to the short tube, means for circulating oil cyclically through the short tube and part of the longer tube, the upper portion of the longer tube being extended above the circulatory zone, and means for withdrawing vapors from the upper part of the longer tube.

oil to the short tubes, means for circulating oil cyclically through the short tubes and part of the longer tube, the upper portion of the longer tube being extended above the circulatory zone, and means for withdrawing vapors from the upper part of the longer tube.
